CLAIM

We claim the ornamental design for an axial turbine housing for a rotary atomizer for a painting robot, as shown and described.

DESCRIPTION

FIG. 1 is a side perspective view of an axial turbine housing for a rotary atomizer for a painting robot, in which the ornamental design of the front and sides of the axial turbine housing is symmetric about the axis thereof; and

FIG. 2 is a rear perspective view of the axial turbine housing of FIG. 1.

FIG. 3 is a side view of the axial turbine housing of FIG. 1; and,

FIG. 4 is a rear plan view of the axial turbine housing of FIG. 1.
